WELL CEMENTING SHOE

Reuben C. Baker, Coalinga, Calif., assignor to
 Baker Oil Tools, Inc., Huntington Park, Calif.,
 a corporation of California

Application December 12, 1938, Serial No. 245,235

4 Claims. (Cl. 166—9)

This invention relates to apparatus employed during the drilling of oil wells.

It is the principal object of the present invention to improve the construction of cementing shoes for well casings by incorporating therein a simple and inexpensive means insuring equal distribution of the cement around the shoe as it discharges therefrom and thereby prevent channelling of the cement in the annular space between the casing and the bore.

One form which the invention may assume is exemplified in the following description and illustrated by way of example in the accompanying drawing, in which:

15 Fig. 1 is a view in elevation and section of a cementing shoe embodying the preferred form of my invention.

Fig. 2 is a bottom view thereof.

Referring more particularly to the accompanying drawing, 10 indicates a casing shoe which in effect is a cylindrical steel member adapted to be attached to the lower end of a string of well casing as in standard practice. Within the shoe is cast a concrete or cementitious plug 11, the lower end of which is rounded to form a guide 12. Secured concentrically within this plug 11 is a tube 14 formed of aluminum or other drillable material. Preferably this tube is anchored into the concrete plug 11 and it forms a passageway therethrough.

In the present instance I have shown the device as being a guide shoe not fitted with a back-pressure valve. However, it is obvious that the present invention is applicable to float shoes and cementing shoes of all characters.

Securely fastened within the tube 14 is a spiral assembly 15 formed of cast aluminum or any other suitable drillable material. This spiral assembly 15 consists of three blades spirally formed to form spiral passageways in the tube 14, adjacent its lower end so that as fluid is discharged downwardly under pressure through the tube 14, it will assume a spiral motion as it emerges from the bottom of the tube, and thereby insure equal distribution of the cement in the well bore.

This is very advantageous because if the cement is not equally distributed around the shoe, channels are liable to occur in the cement after it is set through which water may migrate. By

my present invention I have provided a very simple and inexpensive medium for accomplishing the equal distribution of the cement around the shoe and which I have found to be very efficient in operation.

While I have shown the preferred form of my invention, it is to be understood that various changes may be made in its construction by those skilled in the art without departing from the spirit of the invention as defined in the appended claims.

Having thus described my invention, what I claim and desire to secure by Letters Patent is:

1. In combination with a casing shoe, a guide member secured thereto and having a central 15 passageway formed longitudinally thereof, means in said passageway dividing said passageway into a plurality of relatively steep spirally directed passages to give fluid discharged downwardly therethrough a whirling motion as it emerges 20 therefrom.

2. In combination with a casing shoe, a plug secured therein and having a central longitudinal passageway, spiral blades fixed in said passageway to divide the same into a plurality of relatively 25 steep helical passages to impart a spiral motion to fluid forced downwardly therethrough as it emerges from said passageway.

3. In combination with a casing shoe, a cementitious plug cast therein, a tube secured to said 30 plug and extending longitudinally thereof and forming a passageway therethrough, said passageway being divided into a plurality of relatively steep helical passages to impart a whirling motion to fluid pumped downwardly there- 35 through.

4. In combination with a casing shoe, a cementitious plug cast therein and being formed with a guide-shaped lower end, a tube of drillable material secured concentrically of said plug and extending longitudinally therethrough, a plurality of blades of drillable material secured in said tube, the outer marginal edges of said blades bearing against the inner circumference of said tube and dividing the interior of said tube into a plurality of relatively steep spiral passageways to give fluid pumped downwardly through said tube a whirling motion as it emerges from the tube.

REUBEN C. BAKER.
